Primary Examiner — Kevin Rudzinski

(74) Attorney, Agent, or Firm — Lerner, David, Littenberg, Krumholz & Mentlik, LLP

(57) **CLAIM**

The ornamental design for a display screen or portion thereof with graphical user interface, as shown and described.

DESCRIPTION

The FIGURE is a front view of a display screen or portion thereof with graphical user interface according to our design. The dot-dash broken lines shown in the drawings illustrate the display screen and the evenly spaced broken lines illustrate portions of the graphical user interface. All broken lines form no part of the claimed design.
